APPARATUS FOR PRODUCING A
DRY FIXED GASFrank J. Nolan, Bridgeport, Conn., assignor to
Electro-Gas Corporation, Rochester, N. Y., a
corporation of New York

Application June 7, 1933, Serial No. 674,726

9 Claims. (Cl. 261—85)

My invention relates to an apparatus for producing from liquid hydrocarbons, especially from the gasoline fractions, a dry fixed gas of the type disclosed in my pending application Serial 5 No. 674,235, filed June 3, 1933.

According to the present invention, air is drawn over one or more rapidly rotating wicks which are fed by capillary attraction from a source of liquid hydrocarbons.

10 The object of this invention is to produce a dry fixed gas which contains all the ingredients of the liquid hydrocarbon used, which gas is stable within the limits of normal atmospheric temperatures.

15 A further object is to provide a simple and inexpensive apparatus for accomplishing this result.

Further objects and advantages will appear more fully from the following description when taken in conjunction with the accompanying 20 drawing which forms a part thereof.

In the drawing:

Fig. 1 is a side elevation of my apparatus.

Fig. 2 is a cross section on the line 2—2 of 25 Fig. 1.

Fig. 3 is a cross section on the line 3—3 of Fig. 2.

20 The invention comprises a vaporizer A, a motor B and a pump C. The vaporizer consists of a cylindrical casing 2 mounted above a liquid hydrocarbon tank 4 and communicating therewith by a circular opening 6 of less diameter than the casing. A vertical shaft 8 is rotatably mounted in the top or cover 10 of the casing 2 and its lower end is supported by a bearing 12 in 30 the tank 4.

35 Mounted on the shaft 8 is a rotor comprising an upper disc 14 and a lower disc 16 connected and held in spaced relation by bolts 18 or the like. Below and secured to the lower disc is a downwardly extending cylindrical casing 20 located in and substantially filling the opening 6. The casing 20 extends substantially to the bottom of the tank 4 and its bottom wall 22 is provided with apertures 24 to permit liquid hydrocarbon to rise in the casing 20. Wicks 26 are arranged with their lower ends in the casing 20, while their central portions extend radially outward between the discs 14 and 16. The upper ends of the wicks are secured near the outer edges of the discs to the bolts 18 as by wire 27. The space between the outer edges of the discs 40 may also be closed by a screen 28.

45 The shaft 8 is provided with an internal air passage 30 having inlet openings 32 above the cover 10 and outlet openings 34 between the

discs. The cover 10 is provided with a gas outlet 36. The tank 4 may be filled at 38 and is supplied with a drain tap 40.

The shaft 8 is connected to the shaft 42 of the rotor of the motor B. At the other side of 5 the motor the shaft 42 drives the pump C. This pump is preferably of the constant pressure type, for instance, a sliding vane pump. The pump inlet is connected by a pipe 44 to the gas outlet 36, and delivers the finished gas through outlet 46 controlled by a valve 48.

The operation of my device is as follows: The starting of the motor causes the pump to draw air through the shaft 8 and radially outward between the discs over and through the wicks 15 26. As the air passes over the wicks it absorbs the constituents of the gasoline which is present on the wicks in finely subdivided form, forming a dry fixed gas of the type described in my application referred to above. This gas is stable, 20 and contains no carbon monoxide. It has a high fuel value, up to 500 B. t. u. per cubic foot, and can be made very cheaply. Even low grades of gasoline will be completely absorbed by the air, so that the less volatile constituents are not 25 wasted.

As the liquid hydrocarbon is absorbed, further fuel is fed to the upper ends of the wicks by capillary attraction. This feeding is enhanced by the centrifugal force generated by the rotation. Furthermore, this centrifugal action tends to throw off the liquid from the wick and break it up into an easily absorbed condition. 30

As I have explained in my application above referred to, the passage of air over a series of 35 wicks which are fed by capillary attraction prevents the air from becoming over-saturated and depositing the less volatile constituents. Nevertheless, the feed of a sufficient quantity of liquid is assured. The present arrangement is somewhat more compact, and the centrifugal action keeps up the feed so that the finished gas will contain a sufficient proportion of hydrocarbons. In addition, the fact that the pump and rotor 40 of the vaporizer are driven at the same speed 45 will increase the feed of liquid to the wicks as the velocity of the air flow increases.

By my invention, therefore, the air passes over a rapidly rotating wick, fed partly by capillary action and partly by centrifugal force; the latter 50 increasing proportionately to increases in the volume of air passing over the wicks. Preferably, the size and quality of the wicks and the speed of the rotor are so chosen that the amount of liquid exposed to any part of the air is no more 55

than that necessary to saturate such part of the air. This causes a proper feed of liquid, yet prevents the air from depositing heavier fractions which it may have absorbed in exchange for lighter ones.

While I have described herein one embodiment of my invention, I wish it to be understood that I do not intend to limit myself thereby except within the scope of the appended claims.

10 I claim:

1. In an apparatus for forming a dry fixed gas from liquid hydrocarbons, a wick mounted to turn about a vertical axis, means to rotate said wick, a container for liquid hydrocarbon, said wick

15 extending into said container, and means to draw air radially outward in contact with said wick at a velocity substantially directly proportional to the speed of rotation of said wick.

2. In an apparatus for forming a dry fixed gas 20 from liquid hydrocarbons, a vertical shaft, means to rotate said shaft, a pair of vertically spaced discs mounted on said shaft, a container for liquid hydrocarbon below said discs, a plurality of wicks having their upper ends between and secured to said discs and their lower ends extending into said container, and means to draw air radially outward between said discs.

3. In an apparatus for forming a dry fixed gas 30 from liquid hydrocarbons, a vertical shaft, means to rotate said shaft, a pair of vertically spaced discs mounted on said shaft, a container for liquid hydrocarbon below said discs, a plurality of wicks having their upper ends between and secured to said discs and their lower ends 35 extending into said container, said shaft having a passage therein and openings connected to said passage above and between said discs, and means to draw air past the outer edges of said discs.

4. In an apparatus for forming a dry fixed gas 40 from liquid hydrocarbons, a casing, a vertical shaft extending through said casing, means to rotate said shaft, a pair of vertically spaced discs mounted on said shaft within said casing, a container for liquid hydrocarbon below said casing, 45 said casing having an opening therein communicating with said container, a plurality of wicks having their upper ends between and secured to said discs and their lower ends extending through said opening into said container, and means to draw air radially outward between said discs.

5. In an apparatus for forming a dry fixed gas 50 from liquid hydrocarbons, a casing, a vertical shaft extending through said casing, means to rotate said shaft, a pair of vertically spaced discs mounted on said shaft within said casing, a container for liquid hydrocarbon below said casing, 55 said casing having an opening therein communicating with said container, a plurality of wicks having their upper ends between and secured to said discs and their lower ends extending through said opening into said container, means to admit air at a point adjacent said shaft between said discs, and means to draw off air from a point in 60 said casing above said discs.

6. In an apparatus for forming a dry fixed gas

from liquid hydrocarbons, a casing, a vertical shaft extending through said casing, means to rotate said shaft, a pair of vertically spaced discs mounted on said shaft within said casing, a container for liquid hydrocarbon below said casing, 5 said casing having an opening therein communicating with said container, a plurality of wicks having their upper ends between and secured to said discs and their lower ends extending through said opening into said container, said shaft having a passage therein and openings connected to said passage above and between said discs, and means to draw off air from a point in 10 said casing above said discs.

7. In an apparatus for forming a dry fixed 15 gas from liquid hydrocarbons, a vertical shaft, a motor connected to said shaft to rotate the shaft, a pair of vertically spaced discs mounted on said shaft, a container for liquid hydrocarbon below said discs, a plurality of wicks having their upper ends between and secured to said discs and their lower ends extending into said container, and means driven by said motor to draw air radially outward between said discs.

8. In an apparatus for forming a dry fixed 20 gas from liquid hydrocarbons, a casing, a vertical shaft extending through said casing, means to rotate said shaft, a pair of vertically spaced discs mounted on said shaft within said casing, a container for liquid hydrocarbon below said casing, 25 said casing having an opening therein communicating with said container, the lower disc having a downward cylindrical extension thereon extending through said opening into said container, said cylindrical extension having openings therein, a plurality of wicks having their upper ends between and secured to said discs and their lower ends within said cylindrical extension, 30 means to admit air at a point adjacent said shaft between said discs, and means to draw off air 35 from a point in said casing above said discs.

9. In an apparatus for forming a dry fixed gas 40 from liquid hydrocarbons, a casing, a vertical shaft extending through said casing, means to rotate said shaft, a pair of vertically spaced discs mounted on said shaft within said casing, a container for liquid hydrocarbon below said casing, 45 said casing having an opening therein communicating with said container, the lower disc having a downward cylindrical extension thereon extending through said opening into said container, the bottom wall of said cylindrical extension having openings therein, a plurality of wicks having their lower ends within said cylindrical extension, their intermediate portions extending radially outwardly between said discs, and their outer ends arranged substantially vertically and secured to said discs at points adjacent the outer edges of the discs, means to admit air 50 at a point adjacent said shaft between said discs, and means to draw off air from a point in said casing above said discs.
